3 Claims. (Cl. 250—36)

The frequency of a self maintained thermionic valve generator depends slightly on the voltages operating the valve, but is always approximately equal to the natural frequency of the oscillatory circuit. The frequency is thus a function of the circuit and of the valve. The valve affects the frequency both by the curvature of its characteristic and by the capacity of its electrodes. This invention is a device for rendering the frequency sensibly independent of the curvature of the characteristic. For simplicity of description attention will be limited to the dynatron type of generator, but the invention is not limited to generators in which the potential of only one electrode is fluctuating. The dynatron generator consists of an oscillatory circuit connected between a battery and the anode of a valve which is arranged to have a characteristic with a negative slope; if the resistance of the circuit is less than a certain value depending on the said negative slope, an alternating current is produced of frequency approximately equal to that natural to the circuit. The current entering the anode consists of two portions, one which passes to the cathode by an electron stream and one which passes by a capacity current. We here consider only that portion which passes by an electron stream. Let the relation between this portion i of the current and the anode potential v be expressed by the equation

$$i = \alpha v + \beta v^2 + \gamma v^3 + \delta v^4 + \epsilon v^5 + \dots$$

where α, β, γ etc., are constants depending on the valve. If $v = V_1 \sin pt$, then on substitution we find that i is of the form $I_1 \sin pt + \text{higher harmonics}$, where I_1 is the amplitude of the fundamental, and therefore the fundamental component of i is in phase with v . At every instant of time the alternating potential difference across the circuit is equal and opposite to the alternating potential difference of the anode and hence if $v = V \sin pt$, the current entering the circuit is in phase with the potential difference across it. Accordingly, if v contained no higher harmonics the frequency would necessarily be such that

$$\frac{pL}{R^2 + p^2 L^2} = \frac{1}{pC}$$

where R and L are the resistance and inductance of the coil and C is the capacity of the condenser.

The voltage $V_1 \sin pt$ produces higher harmonic currents which must flow through the oscillatory circuit and thereby produce higher harmonic components of anode potential. It is

essential to realize that the fractional amplitudes of these voltage harmonics are necessarily very small, since the circuit has a small power factor. Thus if I_1 and I_n are the fundamental and the nth harmonic amplitudes of i it is well known that

$$\frac{V_n}{V_1} = \frac{nI_n}{F(n^2 - 1)I_1}$$

where $F = R/pL$ is the power factor of the circuit. In general F is of the order of 1/100 and hence in general V_n/V_1 is less than $1/n\%$, since I_n will probably be less than I_1 . Hence although the harmonics of i may be large, the harmonics of v are necessarily very small. Consequently, the harmonics of v affect the harmonics of i very little and these are substantially the same as if $v = V_1 \sin pt$.

When

$$v = V_1 \sin pt + \sum_{n=2}^{\infty} v_n \sin (npt + \lambda) \quad 20$$

and $i = \alpha v + \beta v^2$ etc. analysis shows that

$$i = I_1 \sin pt = I_1' \cos pt + \sum_{n=2}^{\infty} I_n \sin (npt + \theta) \quad 25$$

There is now a term $I_1' \cos pt$ which is in phase quadrature with the voltage across the circuit and consequently the frequency must be greater than or less than that calculated previously; the discrepancy is a function of α, β, λ etc.

If V_2, V_3 etc. were all zero, the curve representing a half cycle of i would be symmetrical about the mid ordinate and would be represented by the Fourier series $i = I_1 \sin pt + I_2 \cos 2pt + I_3 \sin 3pt$ etc. According to this v would be of the form $v = V_1 \sin pt + V_2 \sin 2pt + V_3 \cos 3pt + V_4 \sin 4pt$ etc. This curve for v is not symmetrical about the mid ordinates and will produce a current curve which is not quite symmetrical about the mid ordinate. The dissymmetry of the current curve must be due mainly to a small term $I_1' \cos pt$, which is responsible for making the frequency dependent on α, β, λ etc.

If v had been of the form $v = V_1 \sin pt + V_2 \cos 2pt + V_3 \sin 3pt$ etc. the curve would have been symmetrical about the mid ordinate and the term $I_1' \cos pt$ would not have existed. In order to prevent the term $I_1' \cos pt$ from existing it is necessary to change by a quarter cycle the phase of the potential differences due to the harmonic currents produced by the voltage $V_1 \sin pt$. This invention consists in making the phase of the harmonic voltages such that they do not affect the frequency of the generator. This can be

done by arranging the oscillator circuit so that it is in acceptor resonance to the higher harmonics. Then the harmonic potential differences will have the desired phase relationship with the harmonic currents and further their amplitudes will be rendered negligible compared with their previous value. A close approximation to this condition can be brought about by dividing the aforementioned condenser C into parallel portions and joining each in series with an inductance such that one branch will be in resonance to the second harmonic and the other branch to the third harmonic and so on. The inductance of the branch tuned to the second harmonic should be shunted by a small condenser which makes this branch capacitative to the, say, 4th, and higher harmonics.

If the term $I' \cos pt$ could be prohibited entirely, then p^2 could be made equal to $1/LC$ by making the power factor of the condenser branch equal to the power factor of the inductive branch and then the frequency would depend only on L and C and be independent of the valve and the resistance of the circuit. This invention also includes making the power factor of the condenser branch such that the whole network has unity power factor when $p^2=1/LC$; the frequency is thereby rendered independent of small changes of resistance.

The invention is illustrated in the accompanying drawing which shows diagrammatically one form of network suitable for use as the external anode tuning impedance in a thermionic oscillation generator in accordance with this invention.

The network shown in the accompanying drawing may be connected between the anode of a valve arranged to exhibit negative resistance (a so-called dynatron) and the positive terminal of the anode battery for said valve, the point A being connected to the anode of the valve and the point B to the said positive terminal of the anode battery.

The network shown in the accompanying figure comprises similar inductance coils of inductance L and resistance R each coil being represented in the figure as a resistance R in series with an inductance L . The main condenser of the whole network is the condenser C_1 and this is in series with a resistance P to be referred to later. Each of four of the inductance coils has in series therewith a condenser marked C_2 C_3 C_4 or C_5 and the whole network is such as to be as a whole in shunt resonance (so-called "stopper resonance") to the working frequency

$$n = \frac{P}{2\pi}$$

The condensers C_2 C_3 C_4 C_5 are the values given by the following equations:

$$4p^2LC_2=1$$

$$9p^2LC_3=1$$

$$16p^2LC_4=1$$

$$25p^2LC_5=1$$

Thus the series branches consisting each of inductance L and resistance R and capacity C_2 or C_3 or C_4 or C_5 is in acceptor resonance either to the second, third, fourth, or fifth harmonic of the working frequency, and therefore at each of these harmonic frequencies there will be a branch presenting a non-inductive impedance of value R . Therefore at each of the harmonic frequencies the network as a whole will present an impedance consisting of a predominantly inductive or ca-

pacitative impedance of high value shunted by a small resistance R which may be made so small relative to the joint impedance of the rest of the circuit that it is for practical purposes sufficient to assume that the total effective impedance between the points A and B at each of the harmonic frequencies in question is that of a non-inductive resistance of value R . At the fundamental or working frequency n each of the acceptor branches presents a capacitative impedance and is thus equivalent to a condenser added in parallel with the condenser C_1 . Owing, however, to the fact that each of these added capacitative branches includes a resistance R the added condenser is in effect one of relatively poor power factor. It may be calculated that at the working frequency n the total effect from this point of view of the acceptor branches is equivalent to that of a condenser of capacity

$$\frac{34}{15}C_2$$

whence it follows that the effective capacity K of the whole network is

$$C_1 + \frac{34}{15}C_2$$

since $p^2LK=1$; $K=4C_2=2.3077C_1$. Thus if the acceptor branches were removed it would be necessary to increase the capacity of C_1 to a value $2.3077C_1$ in order to maintain the reduced network (consisting of C_1 in parallel with LR) in stopper resonance at the frequency n . Since at the fundamental frequency n the acceptor branches are equivalent to a portion of the total effective capacity K this capacity will have an appreciable power factor and owing to the fact that the acceptor branch LC_2 carries a much greater fraction of the total capacity current than the higher harmonic acceptor branches LC_3 or LC_4 the branch LC_2 will have most effect in increasing the total effective power factor. It may be calculated that the effective resistance of the whole network is $1.1325R$.

The current through the higher harmonic acceptor branches is so small a fraction of the total capacity current—for example, in the case illustrated and at ordinary wireless frequency, the current through the branch LC_5 is relatively so small—that the energy waste therein is a negligible fraction of the total energy loss whence it follows that the resistance of the coils of the upper harmonic acceptor branches—in the example specified the resistance of the coil in the branch LC_5 , is not important. For operation at the shorter wave lengths the capacity required theoretically for the branch C_5 may be inconveniently small and as a matter of practical convenience therefore it may be of advantage to make the coil of the branch LC_5 smaller than that in the other branches so as to allow C_5 to be correspondingly increased, e. g. the coil of the branch LC_5 may be $\frac{1}{2}L$.

It has been previously pointed out that stopper circuit resonance in the network as a whole will occur at the frequency given by the equation $p^2LK=1$. If the power factor of the effective condenser branch be equal to that of the effective inductive branch. The provision of the resistance P shown in the accompanying drawing enables this requirement of equality of power factor to be satisfied, the said resistance P being in the case specifically illustrated and described of value $0.868R$. With a resistance P of this value the

effective impedance between the points A and B at the fundamental frequency n will be

$$\frac{P^2 L^2}{2R}$$

5 Although, theoretically, increased advantage will be obtained by increasing the number of acceptor branches, in practice a comparatively limited number of branches is sufficient and increase 10 in the number of branches beyond a four or five branched circuit does not in ordinary circumstances substantially improve the practical results while constructional difficulties and disadvantages are obviously increased.

15 I claim:

1. An oscillation generation circuit comprising an electron discharge device having an electrical network in the path traversed by the oscillatory energy, said network comprising an inductive 20 branch, a capacitive branch in parallel with said inductive branch and a plurality of series resonant branches resonant to harmonics directly in shunt with said inductive and capacitive branches, said network being anti-resonant to the 25 fundamental frequency but series resonant to said harmonics.

2. A dynatron oscillation generation circuit comprising an electron discharge device including an anode, cathode, and screen grid electrode, 30 a source of potential for maintaining said screen grid at a higher positive potential than said anode, an electrical network comprising a plurality of series branches connected in parallel located between said anode and cathode, each of said 35 branches being resonant to a harmonic frequency

of the generated energy and comprising an inductance and a condenser in series, whereby at predetermined different harmonic frequencies there will be a branch presenting a non-inductive impedance substantially of the value of the resistance in the branch, each of said branches presenting a capacitive impedance to the working frequency, and a main condenser in parallel with an inductance, both said main condenser and its parallel connected inductance being in shunt relation with said parallel combination of series branches, the electrical network as a whole being anti-resonant to the working frequency.

3. An oscillation generation circuit comprising a multi-electrode electron discharge device including anode and cathode electrodes, an electrical network comprising a plurality of series branches connected in parallel located between said anode and cathode, each of said branches being resonant to a harmonic frequency of the generated energy and comprising an inductance and a condenser in series, whereby at predetermined different harmonic frequencies there will be a branch presenting a non-inductive impedance substantially of the value of the resistance in the branch, each of said branches presenting a capacitive impedance to the working frequency, and a main condenser in parallel with an inductance, both said main condenser and its parallel connected inductance being in shunt relation with said parallel combination of series branches the electrical network as a whole being anti-resonant to the working frequency.
